UNITED STATES PATENT OFFICE

134,481

DESIGN FOR AN ELECTRIC LIGHTING FIXTURE

Gustave W. Borkland, Chicago, Ill.

Application February 9, 1942, Serial No. 105,722

Term of patent 14 years

To all whom it may concern:

Be it known that I, Gustave W. Borkland, a citizen of the United States, residing at Chicago, in the county of Cook and State of Illinois, have invented a new, original, and ornamental Design for an Electric Lighting Fixture, of which the following is a specification, reference being had to the accompanying drawing, forming a part thereof.

In the drawing,

Figure 1 is a perspective view as seen from underneath of the electric lighting fixture showing my new design;

Fig. 2 is a bottom plan view; and

Fig. 3 is a section on the line 3—3 of Fig. 2.

I claim:

The ornamental design for an electric lighting fixture, substantially as shown.

GUSTAVE W. BORKLAND.
